PAGE 2

FIG. 2

FIG. 3

FIG. 4

FIG. 5

Fig. 1 is a perspective view of a magnetic recorder, showing our new design;

Fig. 2 is a front elevational view;

Fig. 3 is a rear elevational view;

Fig. 4 is a side elevational view, the opposite side having substantially the same appearance; and

Fig. 5 is a top plan view thereof.

The cover, which is lined to indicate transparency in Fig. 1, has been omitted from Figs. 2, 3, 4 and 5 for convenience in illustration.

We claim:

The ornamental design for a magnetic recorder, as shown and described.
